Patented Apr. 13, 1976

239,515

FISHING SIGNAL DEVICE

Theodore Montgomery, Box 43, and Wayne T. Wise,
Box 175, both of Frankfort, S. Dak. 57440

Filed Aug. 14, 1975, Ser. No. 604,873

Term of patent 14 years

Int. Cl. D10—06

U.S. Cl. D10—109

FIG. 1

FIG. 2

FIG. 3

FIG. 5

FIG. 4

FIG. 6

FIG. 1 is a view in perspective as seen from one side, the front and above of a fishing signal device showing our new design;

FIG. 2 is a view in side elevation thereof showing the side opposite that shown in FIG. 1;

FIG. 3 is a view in rear elevation thereof;

FIG. 4 is a view in front elevation thereof;

FIG. 5 is a view in top plan thereof; and

FIG. 6 is a view in bottom plan thereof.

We claim:

The ornamental design for a fishing signal device, substantially as shown.
